GOLF BAG

Louis Salzberg, Newark, N. J., and Edwin J.
Hughes, Jr., Larchmont, N. Y.

Application March 25, 1947, Serial No. 736,916

5 Claims. (Cl. 150—1.5)

1

This invention relates to golf bags.

One object of the invention is to provide a golf bag having individual tubular compartments or pockets for protectively housing the golf sticks against damage by rubbing or by impact against other golf sticks, these compartments further including sections shaped to fit the wooden heads of certain of the clubs.

Another object of the invention is the provision of a golf bag having different rows or series of such tubular compartments disposed internally and externally of the golf bag, and certain of the compartments being removable, or means being provided to furnish additional compartments for the golf sticks.

Another object of the invention is to furnish a golf bag having improved means for mounting a hood so as to permit any of the rows of golf sticks to be conveniently exposed while covering other rows of golf sticks, and the hood being also removable when desired.

Another object of the invention is to construct a golf bag having a main club receiving section and cooperating removable section adapted to contain a series of golf sticks, the removable section being adapted to be conveniently independently carried or to be operatively mounted on the main section of the golf bag.

Another object of the invention is to furnish a golf bag comprising separable portions adapted to house different sets of golf clubs, with the provision of a common hood which may be independently used with either section.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a perspective view of a golf bag embodying the invention with the hood in open position.

Fig. 2 is a vertical longitudinal sectional view of the same with the hood in closed position.

2

Fig. 3 is an edge view in elevation showing the removable section of the golf bag with the hood in section, detached from the bag member and connected to the removable section.

Fig. 4 is a section on the line 4—4 of Fig. 1.

The advantages of the invention as here outlined are best realized when all of its features and instrumentalities are combined, but useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes a golf bag embodying the invention. The same includes a bag member 11 open at the top and having a closed bottom 12 and a longitudinal opening along the edge thereof controlled by a slide fastener 13. The bag member may be made of any suitable flexible material reinforced by a metal frame including ring or loop members 15 and 16 at the rim and at the bottom 12, these loop members being rigidly interconnected by vertical rods 18, thus imparting a suitable degree of stiffness to the bag member 11. A shoulder strap 19 of any suitable type may be connected to the bag member 11 and the latter may also carry a ball pocket 20 closed by a slide fastener 21. A handle 22 may be connected to the bag member. It will be understood that as thus far described, the structure is conventional.

The bag member 11 comprises side walls 23 and 24 which are relatively plane or slightly curved. To the wall 24 is connected a sheet of fabric 25 extending substantially throughout the length of the bag, the connection being by means of a longitudinal series of spaced lines of stitching 26, and the arrangement being such as to provide a series of vertical tubular pockets 27 which are permanently open at the top and are closed at the bottom in any suitable manner.

Associated with the other side wall 23 is a plurality of series of golf stick pockets 29 and 30 which are of narrow elongated form, like the pockets 27. However, the pockets 29 which are disposed internally of the bag member 11 are formed with upper sections 31 which extend

above the mouth of the bag member 11, these sections 31 being enlarged and shaped to readily receive and snugly fit the wooden heads of golf sticks. Each of these sections may have an opening closed by a slide fastener 32 to facilitate removal of a golf club. The pockets 29 may be formed of separate strips of fabric or of a single sheet of canvas 33, undulated and connected to a companion flat sheet of fabric 34 by a plurality of spaced vertical lines of stitching 35 to thus produce the tubular pockets 33 which are closed in any suitable manner at their lower ends. While the member 33 may be thus directly secured to the bag wall 23, it is preferred that it be connected to a separate member 34 for reasons hereinafter apparent. The tubular pockets 33 are formed in a similar manner by a pair of companion fabric sheet members 36, 37 interconnected by vertical-spaced lines of stitching 38, and while the member 36 may be thus secured directly to the bag wall 23, it is preferred that its companion wall 37 be independent of such wall for reasons hereinafter described.

Either or both of the sections 29 and 30 are removable with respect to the bag member 11. Accordingly, the purchaser may acquire only the bag member 11 and subsequently add either or both of the sections 29 and 30 as may be necessary. Similarly, other pockets or sections for additional golf sticks may be added from time to time.

Preferably sections 29 and 30 are interconnected to form a unit 40 as shown in Fig. 3. Such interconnection is preferably by means of a suitable flexible portion or strip such as 41. Interconnecting means may further provide for the separation of these sections so that one can be used without the other. A buckle or other detachable fastener means 42 desirably provides an adjustable connection with the section 30 whereby the strap 41 may form a loop of any desired length. This will permit the operator to readily carry the unit 40, utilizing the strap as a handle or as a shoulder strap. If desired, a detachable fastener means 43 of any suitable nature may connect the strap to the section 29. A portion of this fastening means 43 may be utilized to directly connect the section 29 to the golf bag in any desired position. Similarly a section of the fastening means 42 may be utilized to separately connect the section 30 to the bag member 11. A companion fastening element of any suitable type is indicated, generally at 44 for such complementary uses with the devices 42 and 43. The preferred use of the sections 29 and 30 is as a unit 40 and to facilitate such use, a detachable fastening connection 45 may be provided to interconnect the section 30 with the section 29 against unduly free lateral movement. Generally the fastening 45 may be in the nature of a strap detachably connected at 46 to the section 29. This strap may also be detachably connected at 47 to the bag member 11 to prevent free swinging of the section 30.

When the unit 40 is assembled with the bag member 11, the strap 41 may be suitably adjusted to pass over the rim loop 15 and engage the fastening means 42 and thus to suspend the section 29 internally of the bag member and the section 30 externally thereof. If the weight of the sections be unequal, the strap 45 will assist in suitably anchoring the unit 40.

A hood 50 may comprise two sections 51 and 52 seamed together at 53 into which seam is connected a freely depending strip member 54 engaged by any detachable fastener 55 with a flap 75

member 56 that is suitably connected to the bag member 11. The parts 54, 56 are thus internal of the head and are adjacent to the center thereof and they permit free lateral relative movement of the walls or sections 51 and 52 to expose any of the series of pockets 27, 29, and 30. This may be facilitated by a longitudinal opening in the hood closed by a solid fastener 57. It is understood that the hood is flexible and the showing in the drawing in which it is above its normal resting position is employed for clarity in the drawing. The hood may enclose the entire upper portion of the device 10 or it may only cover any desired section thereof. The hood may be interchangeably connected to the unit 40 shown in Fig. 3 by opening the fastening 55 and connecting a portion thereof to the section 29 by detachable fastening means indicated at 58. Thus the hood may be employed either with the bag member 11 or with the unit 40; or with both jointly.

It will now be perceived that the invention provides a golf bag having means for holding clubs in a series of different rows so as to afford individual protection for the clubs against marring each other, and with a special provision for protection of the wooden heads of the clubs. The invention also provides an improved means which furnishes two carrying structures for golf sticks, that may be combined into one unitary device or golf bag. Accordingly such an arrangement will permit the golf bag to be stored at the club house, with the selected clubs placed in the removable section and carried about with entire convenience particularly as the weight will be considerably less. Two persons such as a husband and wife may use the golf bag jointly, one carrying the bag member 11 and the other the unit 40, with miscellaneous articles stored in the bag member 11, the space for which is substantially increased by the removal of the section 29. The unit 40 may be conveniently carried in any well-known manner at the strap 41 and may be quickly swung on to the bag member 11 to form a complete device 10. Such device may function as a complete unitary structure as if all of its parts were permanently interconnected. The hood 50 can be interchangeably connected to the bag member 11 or to the unit 40 in operative position, and when the unit 40 is assembled with the bag member 11, the hood may remain attached to either, with its sides 51 and 52 adapted to be lifted to expose any desired row of clubs. The hood member may also be completely detached and stuffed into the bag member 11.

We claim:

1. A golf bag having a relatively stiff bag member, removable unitary means comprising spaced golf club holding tubular elements one of which is in the bag member and the other outside of the same, an elongated flexible portion interconnecting the elements at their upper portions, the bag member having a top opening having a stiff rim, and the elongated flexible portion extending over and resting on the rim, whereby the removable means can be separated from the bag member and carried with the flexible portion over one's shoulder.

2. A golf bag according to claim 1 including means detachably interconnecting the elements adjacent to the lower ends thereof.

3. A golf bag according to claim 1 including a fastener portion on the external element adjacent to the lower end thereof, the lower portions of the bag member and of the internal ele-

ment having respective fastener means complementary to the fastener portion for releasably engaging the same.

4. A golf bag according to claim 1 including a removable hood, and means for selectively connecting the hood to the removable means and to the bag member, whereby the hood can cover either, the hood being of sufficient size to cover both the removable means and the bag member when the removable means is mounted on the bag member.

5. A golf bag according to claim 1 including a removable hood for the bag member, a fastener element connected to the hood internally of the hood and adjacent to the center thereof, and means cooperating with the fastener element to selectively connect the hood to the bag member or to the removable means.

LOUIS SALZBERG.
